(57) **CLAIM**

The ornamental design for a device and device body for mechanical fractional ablation of the skin, substantially as shown and described.

DESCRIPTION

FIG. 1 is a front view of a device for mechanical fractional ablation of the skin showing our new design.

FIG. 2 is a back view of the device body of FIG. 1.

FIG. 3 is a right side view of the device body of FIG. 1.

FIG. 4 is a left side view of the device body of FIG. 1.

FIG. 5 is a top view of the device body of FIG. 1; and,

FIG. 6 is a bottom view of the device body of FIG. 1.

The broken line showing of portions of the device for mechanical fractional ablation of the skin depicts environment and forms no part of the claim.
